UNITED STATES PATENT OFFICE.

SAMUEL WILSON HEATON, OF PHILADELPHIA, PENNSYLVANIA.

FLOORING.

No. 885,751.

Specification of Letters Patent. Patented April 28, 1908.

Application filed April 2, 1906. Serial No. 309,320.

To all whom it may concern:

Be it known that I, SAMUEL WILSON HEATON, a citizen of the United States, residing at Philadelphia, in the county of Philadelphia and State of Pennsylvania, have invented certain new and useful Improvements in Flooring, of which the following is a specification.

My invention relates to that class of block 10 floors in which the blocks are laid on and interlocked with an adhesive foundation, such as mastic or asphaltum, and are interlocked with each other in the desired pattern or arrangement.

15 The object of the invention is to so shape the blocks that they may be conveniently and accurately cut in the process of their manufacture, may be rapidly laid and assembled to form the floor with close joints between the blocks, and will maintain their uniform level to produce an even and durable floor, at the same time cutting off the mastic from access to the surface of the floor.

25 Heretofore blocks have been formed for floors of this character having mastic engaging grooves near the bases of the blocks, but without continuous or integral side tongues and grooves. In such constructions any swelling or warping of the blocks causes their

30 side edges to get out of level with each other, and in case of the disengagement of the end tongue of a block with the side tongue of the next block the former block would become entirely loose. The mastic base has been, in

35 many constructions, chiefly relied upon to maintain the blocks in position. In some cases the blocks have also, as above indicated, been provided with end tongues to interlock with the sides of other blocks to

40 keep the blocks in place. But these methods have been found to be unsatisfactory, especially with the long blocks preferably employed, which are liable to spring away from the mastic at points between the end tongues.

45 Dowels have also been employed, but this method is expensive, requires more time for the laying of the floor, and renders the surface of the floor less even unless considerable care is taken in the locating and fitting of the 50 holes and dowels.

According to my improvement the adhesive base is aided in keeping the block in place, and the floor level, by a substantially continuous engagement along the full length 55 of the block by a side tongue, which enters a corresponding side groove or end groove in

another block. I thus insure that the desired close union between the mastic and all parts of each block shall be maintained under practically all conditions of use. I also effect- 60 ually cut off the mastic, or oils therefrom, from access to the surface of the floor.

The invention consists in the parts and combinations thereof hereinafter set forth and claimed.

In order to make my invention more clearly understood I have shown in the accompanying drawings means for carrying the same into practical effect, without limiting my improvements, in their useful applications, to the particular construction which, for the purpose of explanation, I have illustrated.

In said drawings—Figure 1 is a plan view of a portion of a floor embodying my improvements. Fig. 2 is a vertical sectional view, on a larger scale, on line II of Fig. 1. Fig. 3 is a similar view, on line III of Fig. 1. Fig. 4 is a perspective view of one of the blocks. Fig. 5 is a sectional view showing 80 the use of a slip tongue.

Referring to the drawings, A is any suitable foundation, which may be concrete or cement.

B is an adhesive base on the top surface of 85 the foundation A. This is, or may be, a mastic or asphaltum applied in a heated and more or less fluid condition. It may be applied by dipping the bottoms of the blocks successively in a vessel containing the mastic 90 and then applying the blocks, assembling and interlocking them in the desired pattern, to the foundation.

C is one of the blocks, of the preferred shape, seen best in Fig. 4. It is by preference 95 formed with a continuous side tongue 1, a continuous corresponding side groove 2 on the side opposite to the tongue, and with an end groove 3 at each end, all the grooves and the tongue being formed at the same level or 100 horizontal plane. These blocks are capable of being assembled in different patterns, that which is preferred, and for which this block is more especially designed, being the herringbone pattern, shown in Fig. 1, in which the 105 blocks are laid side to side and end to side. In assembling the blocks for this pattern a certain number of them are laid side to side with the tongues 1 interlocking with the grooves 2, the ends of the blocks extending 110 successively beyond the ends of the preceding blocks to accommodate the ends of another

series of blocks laid out at right angles to the first mentioned series. Where an end groove 3 meets a side tongue 1 it interlocks therewith, as seen at 4. At intervals an end groove 3 will meet a side groove 2 and at such point or line 8 there is not a direct interlocking of one block with another. To effect an interlocking at some of these points, where the exigencies of the floor (such as an unevenness 10 of the surface of the foundation A) require that the blocks should be interlocked, I provide short slip tongues 5 to be inserted in a groove 2 and a groove 3 where such grooves come opposite to each other, as seen in Fig. 5. 15 The lines 8 are of short extent, and I have found that an interlocking at such points is not necessary, and only occasionally desirable; for the blocks are otherwise firmly interlocked with each other, and along the lines 8 20 the side of one block is interlocked with the mastic by the groove 6 hereinafter described. Moreover, by dispensing with any end tongue I attain some economy of material and time in laying, and the blocks are not required to 25 be made rights and lefts but may all be counterparts.

6 indicates the mastic-engaging grooves of usual shape, formed near the bottom of the block at the sides of the same, below the 30 tongue 1 and groove 2. At the ends of the block I prefer to form bevels 7 inclining downwards and inwards from the lower edges of the lower lips of the end grooves 3, to accommodate the mastic and allow of a 35 close fitting of the ends of the blocks. The spaces formed by the bevels 7 prevent any mastic being forced up at the said points 8 and said bevels act to force the mastic into the opposing grooves 6, as indicated in Figs. 40 2 and 3.

It will be understood that that part of my invention which relates to the cutting off of the mastic from access to the surface of the floor along the sides of the blocks may be realized by making the tongues 1 separate 45 from the blocks in the form of slip tongues of the character of that shown at 5, the blocks being grooved on both sides.

What I claim is—

1. A series of blocks for a flooring, to be 50 laid on a mastic base, each of said blocks being formed with an integral side tongue 1, an opposite side groove 2, end grooves 3, downwardly and inwardly extending end bevels 7 below the end grooves, and side 55 grooves 6 below the said tongue and side groove, substantially as and for the purposes described.

2. A wooden block floor consisting of a base of adhesive material, and blocks laid 60 thereon and interlocked with each other, the blocks being each provided with a side tongue and with an opposite side groove, the side tongue of one block being interlocked with the side groove of the next block, and also 65 provided with end grooves certain of which are interlocked with the side tongues of contiguous blocks, and also provided with spaces to receive the adhesive material, such spaces being situated below the side tongues, 70 the blocks having end bevels 7 to force the adhesive material into said spaces, substantially as set forth.

In testimony whereof I affix my signature in presence of two witnesses.

SAMUEL WILSON HEATON.
